UNITED STATES PATENT OFFICE.

GEORGE LEWIS HOLMES, OF CHICAGO, ILLINOIS.

GATE AND CHUTE FOR COAL OR ORE POCKETS.

SPECIFICATION forming part of Letters Patent No. 752,555, dated February 16, 1904.

Application filed March 24, 1902. Serial No. 99,643. (No model.)

To all whom it may concern:

Be it known that I, GEORGE LEWIS HOLMES, a citizen of the United States, residing at Chicago, in the county of Cook and State of Illinois, have invented a certain new and useful Improvement in Gates and Chutes for Coal or Ore Pockets, of which the following is a specification.

My invention relates to gates and chutes for coal or ore pockets, and has for its object to provide certain new and useful improvements.

Figure 1 is a front view. Fig. 2 is a cross-section on line 2 2, Fig. 1. Fig. 3 is a horizontal section near the lower part, Fig. 2.

Like parts are indicated by the same letter in all the figures.

A is the bin or pocket, which consists, for example, of the siding and the vertical beams B B and other necessary and associated parts. This pocket is arranged with an opening C, preferably lined, as indicated at C', and there is an inclined way C' leading into and through the opening. The lower end of this inclined way is properly supported on the cross-beams C' and C'. The opening on the exterior side is provided with an outwardly-projecting downwardly-opening hood composed of the plates D D, firmly fixed in position.

E is a gate having the arc-shaped cut-off portion E', the flat chute portion E'', the end frame-pieces E'' E'', and the curved portion E'', which passes around the shaft, and it is pivoted on the shaft E', which is supported in the bearings E''. On the outer end of this shaft E' is an arm F, attached to the link F', which is in turn pivoted at F'' to the short arm F'', which at one end is pivoted at F''' to the side of the hopper-pocket. F''' is the other end of said arm, pivoted at F'' to the link F' and suspended midway by the loop F'', suspended from the rope F'', which runs over a pulley at F'', which is mounted in the bracket F'', and on the other end of this rope is suspended the counterbalance-weight F''. From the outer extremity of the arm portion F''' depends the rod G, provided with the cross-bars G' G''. These parts all stand normally in the position indicated. By pulling down on the rod G the arm F'' F''' tends to assume a horizontal position

and is lowered at F'', thus lowering the link F' and moving the arm F and rocking the shaft E', so as to bring the gate into the position indicated in dotted lines. The flat chute-like portion E'' of the gate E is such that the material escaping over the top of the gate E is carried away on the chute-like incline E''.

J is an outer chute open at the top, the sides of which overlap the sides of the hood D when the pipe J is raised. It is provided below with the chain J' and above with the rope J'', passing over the pulley J''' on the bracket J'' of the pocket-frame. The other end of the rope carries the weight J''. This chain and rope are preferably secured to the outer extremity of the chute J, which is in the form of a downwardly-curved portion J'' and is provided with the hand-bar J''. The upper end of the chute or spout is journaled on the bushing J'', which projects from the bearing E'' and through which passes the shaft E'. The spout is thus not directly supported on the shaft.

The parts are shown in the position which they would occupy when the supply of coal has been cut off and the last portion of that supply has just passed onto the locomotive. The next step will be to raise the chute J in the position shown in dotted lines, which is done by raising it up by means of the hand-bar J''. In this position the gate operates as a stop to prevent the further flow of the material through the hood and chute; but the last material, as the flow is being interrupted, instead of falling off the top of the gate slides down the incline E'' and out through the chute J. The parts are manipulated respectively by the weights and their connections. When it is desired to furnish a supply of coal to the locomotive by means of the chain J', the chute should be drawn down against the weight J'' in the position shown in full lines. Then by manipulating the rod G by either of the bars G' G'' the gate will be thrown down into the position shown in dotted lines, as indicated above, this action being counterbalanced by the weight F''. The material can now flow out over the incline E'' down the chute J. When a sufficient supply has been obtained, the rod G may be moved up

wardly, whereupon the parts associated with the gate will assume the position shown in full lines and the stream of material will be cut off. It will be observed that the parts are so located that this cut-off takes place not directly at right angles to the flow, but in the direction of the flow, so that the danger of crushing the material between the outer extremity of the gate and the hood is minimized. 5 The gate itself is open near this point, as indicated in Fig. 1, so as to reduce the danger of such crushing action. After the last of the material has escaped the chute J can be thrown up into the position indicated in Fig. 2 in dotted lines. It will also be observed that in my construction the gate is supported on a shaft or rod and not on mere light side pins. This is important as obviating the giving and moving of the parts, which so often results in 10 binding. It will also be seen that the gate is located so that its supporting-point is beyond the point of its engagement with the coal and the line of pressure of the coal on the stop-face E' is approximately through the supporting-shaft. As above stated, the gate closes somewhat in the direction of the flow of material, instead of closing against the flow or directly across its path. It also presents a convex instead of a concave or flat surface 15 to the material, which makes it easier to cut into the stream. By this arrangement the support for the gate is projected clear beyond the outer wall of the pocket, which renders

it easy of access for adjustment or repairs. By placing the gate-supports in the position 35 I have shown it is possible to use a rod, because it is placed below the line of travel of the material, while under other conditions it would impede the flow. The spout not being supported on the shaft, but on the bushings 40 associated therewith, is in much less danger of causing binding or cramping of the parts. It is desirable to have the gate as close to the pocket as possible, and by my arrangement, having the gate work on the arc 45 of a circle it cannot enter the edge of the opening, and thus there is left room for a substantial cross-brace in the frame of the pocket and also for the operation of the movable gate, substantially or largely within the 50 line of such pocket-frame. The lower hooded end of the spout prevents the coal from being thrown out at this point.

I claim—

In a gate and chute for coal or ore pockets, 55 the combination of a gate to cut off the flow of coal with a transverse rod below the bottom of the discharge-way, said gate pivoted on such rod, and an outer spout pivoted concentric with but on pivots independent of the 60 rod.

GEORGE LEWIS HOLMES.
